US00D999668S

(12) United States Design Patent (10) Patent No.: US D999,668 S
(45) Date of Patent: * Sep. 26, 2023

(54) EARRING

(71) Applicant: Venus by Maria Tash, Inc., New York, NY (US)

(72) Inventor: Maria Tashjian, New York, NY (US)

(73) Assignee: Venus by Maria Tash, Inc., New York, NY (US)

() Term: 15 Years

(21) Appl. No.: 29/822,500

(22) Filed: Jan. 10, 2022

Assistant Examiner — Sarah J Ault

(74) Attorney, Agent, or Firm — Dentons US LLP

(57) CLAIM

An ornamental design for an earring, as shown and described.

DESCRIPTION

FIG. 1 is a perspective view of an earring;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

Broken lines shown in drawings illustrate portions of the earring that form no part of claimed design.

1 Claim, 7 Drawing Sheets
